UNITED STATES PATENT OFFICE

JOSEPH E. FALCK, OF CHICAGO, ILLINOIS, ASSIGNOR TO F. H. HILL COMPANY, OF CHICAGO, ILLINOIS, A CORPORATION OF ILLINOIS

BURIAL CASKET

Application filed January 16, 1925. Serial No. 2,721.

The present invention relates to sheet metal burial caskets and has particularly in view the provision of a structure of hermetically sealed character, avoiding penetration by 5 cessorial parts attached to the casket body by screws and bolts, forming such parts integral with the body where possible, within the limits of available sheet sizes and otherwise securing by spot or line welding to the exterior; whereby the presence of plain or tapped bolt and machine screw holes are eliminated, and ornamental securing panels and other external features of configuration are included as integral rather than as additive parts, 15 while the expense of manufacture from standpoints of labor, material and time is very materially reduced, by doing away with many operations heretofore considered necessary.

20 In order that the invention may be understood and appreciated by those skilled in the art, a preferred embodiment of the same is set forth in the following specification and illustrated in the accompanying drawings, 25 wherein;

Fig. 1 represents such a casket in side elevation;

Fig. 2 is an enlarged fragmentary view in elevation of one of the ornamental securing 30 panels showing a handle lug in section on the line 2—2 of Fig. 3;

Fig. 3 is a vertical section through a portion of the casket wall on the line 3—3 of Fig. 2;

35 Fig. 4 is an enlarged sectional detail of the sealing joint between the casket cover and body;

Fig. 5 is a fragmentary cross-sectional view of the casket showing a sealing cover of 40 metal; and

Fig. 6 is a fragmentary longitudinal section through the casket end, showing a sealing cover of glass.

Having particular reference to the drawing, the casket 11 is shown as including generally the side walls 12, the end walls 13, the bottom wall members 14 and 14^a, the sealing cover 15, lid 16, corner panels 17, securing 45 panels 18, handle bars 19, handle arms 20 and handle lugs 21.

Heretofore it has been the practice in the manufacture of burial caskets of sheet metal, to miter and solder or braze the junction line between the side and end walls and also between these walls and the bottom members. 55 It has also been customary to cover the soldered line of juncture by means of panels overlying such joints and affixed to the casket body by screws or bolts. It has also been the practice to secure the handle lugs 60 either directly to the casket wall by means of machine screws or bolts passing through apertures in the walls to the inside of the casket and there provided with nuts or other securing means, or decorative securing panels have 65 been secured in this manner through the casket walls and the handle lugs secured in turn to the panels.

It has been hitherto proposed to provide a sealing cover for the casket beneath the outer 70 lid as, for instance, in Patent 1,483,544 of February 12, 1924, but such provision of sealing means has been associated with a casket which was not itself imperforate but had securing nuts and bolts extending through the 75 walls whereby the sealing function of the cover was rendered ineffective.

In constructing a casket according to my invention, dies are provided which form the side walls 12 and a portion of the bottom wall 80 14 and 14^a integral, imparting at the same time such decorative features by way of contour as may be desired together with longitudinally extending stiffening ribs 22. In similar dies the end walls are formed having an 85 inturned integral flange 23 which overlies and is welded to the bottom portions 14 and 14^a. The corner joint is mitered and brazed or soldered, including the two halves of the decorative corner panels 17, each of which 90 halves along with the decorative securing panels 18 are embossed in the metal when forming the side and end walls.

The handle lugs 21 are U-shaped and have 95 inturned flanges 21^a along both sides which are spot welded as indicated in Fig. 2 to the embossed panels 18, there being no screws or bolts penetrating the casket walls.

A sealing connection is formed between the 100 walls and the sealing cover by welding to a

flange 24 of the casket walls a channel member 25 within the upper grooved surface of which is disposed a rubber sealing strip 26. A flange 27 marginally formed on the cover 15 of Figs. 4 and 5 or the composite cover 15^a of Fig. 6 overlies the rubber strip 26 and is pressed in engagement therewith by the screws 28 of a C-bar or clips 29 through the intermediary of a bearing bar 30. This specific sealing connection is not claimed herein per se, it being substantially that shown in Patent 1,483,544 hereinabove referred to, but it enters as an element into the combination of features by which an effectually sealed casket is provided.

15 The lid member 16 overlies the sealing cover and rests by means of its inturned flange 16^a upon the flanges 24 of the casket proper. It may be secured by means of hinges, screws 20 or in any other operative manner which will not penetrate and break the seal of the casket.

20 In the specification and claims I use the terms welding, spot welding, brazing and soldering as equivalents, they being interchangeable for the uses set forth.

25 I claim:

1. In a handle construction for application to an imperforate metal wall, a U-shaped sheet metal bracket which is provided along 30 both sides thereof with in-turned flanges adapted to be welded to the exterior surface of the wall, and a handle member pivotally attached to both sides of the bracket.

2. In a casket handle construction for application to an imperforate metal wall of a casket, a U-shaped sheet metal bracket adapted to be attached to the exterior surface of the wall, and a depending handle pivotally attached to the sides of the bracket, the handle 40 and the pivotal connection therefor being so arranged with respect to the intermediate part of the bracket as to abut with such intermediate part when the handle is swung upwardly into a substantially horizontal position.

45 In testimony whereof I have hereunto subscribed my name.

JOSEPH E. FALCK.
